UNITED STATES PATENT OFFICE

171,193

WIDE MOUTH VACUUM BOTTLE

Carl Bramming, Nashville, Tenn.

Application June 12, 1953, Serial No. 25,473

Term of patent 14 years

(Cl. D58—8)

To all whom it may concern:

Be it known that I, Carl Bramming, a citizen of the United States, residing in the city of Nashville, county of Davidson and State of Tennessee, have invented a new, original, and ornamental Design for a Wide Mouth Vacuum Bottle, of which the following is a specification, reference being had to the accompanying drawing, forming a part thereof, in which:

Figure 1 is a top plan view of a wide mouth vacuum bottle showing my new design;

Figure 2 is a bottom plan view thereof; and
Figure 3 is a side elevational view thereof.

I claim:

The ornamental design for a wide mouth vacuum bottle, as shown.

CARL BRAMMING.
